UNITED STATES PATENT OFFICE.

JOHN A. JOHNSON, OF WINAMAC, INDIANA, ASSIGNOR OF ONE-HALF TO
EDWIN J. FOREST, OF INDIANAPOLIS, INDIANA.

MOLD-FILLING DEVICE.

No. 818,098.

Specification of Letters Patent.

Patented April 17, 1906.

Application filed August 14, 1905. Serial No. 274,190.

To all whom it may concern:

Be it known that I, JOHN A. JOHNSON, a citizen of the United States, residing at Winamac, in the county of Pulaski and State of Indiana, have invented certain new and useful Improvements in Mold-Filling Devices, of which the following is a specification.

This invention relates to a device employed in connection with molds; and the object of the invention is to direct material to be formed into molded articles into the molds and also to remove the surplus material that remains after the molds have been filled and subsequently to reconvey and deposit said surplus material into the succeeding molds. With this device the dissemination of the material is not only prevented, but also the rehandling thereof.

This invention is particularly applicable on my invention that forms the subject-matter of application for patent on "Mold for forming building-blocks" filed in the United States Patent Office on March 16, 1905, Serial No. 250,456.

25 A device embodying the several parts whereby the advantages sought are attained will first be more particularly described in the annexed specification and the novel features then pointed out in the claims.

30 Referring to the accompanying drawings, which are made a part hereof, and on which similar numerals of reference indicate similar parts, Figure 1 is a top or plan view of one end of the mold-filling device; Fig. 2, a cross-section of the same as seen from the dotted line 2 2 in Fig. 1. Fig. 3 is a front elevation of the device in which the central portion is broken away. Fig. 4 is a cross-section of the device as seen from the dotted line 4 4 in Fig. 4 and shows the parts in opened positions.

45 In the drawings, 1 is a rectangular-shaped base-frame, preferably composed of metal, and forms the support for the pallet-board 2, on which the molding is done, and also supports the mold 3, an upper frame that carries the filling device, as well as said filling device. The base 1, pallet-board 2, and upper frame are similarly constructed as shown and described in my former application 50 above mentioned, and no further reference will be made to them except incidentally with the parts forming the subject-matter of this invention.

A second and upper frame, comprising the

members 5 and 6, which conform to the outline of the base 1, is suitably hinged to the latter by means of the hinges 7. The ends of the member 5 of the upper frame are bent at right angle to the main body and form the ends 8 of said frame. These end-forming members 8 are provided with the hooks 9, which engage and form seats for the pivotally-mounted straps 10, mounted on the member 6 of the upper frame, and form locks for securing the two parts of the upper frame together. The closing of the upper frame incloses the mold, and the latter is securely held while the molding operation is in progress.

Secured to by means of the bolts 12 and 13 moving with the member 5 of the upper frame is a hopper-carrying frame that comprises the side members 14 and the tying-cleats 15. The members 14 are provided with the guideways 17, that receive the slides 18, secured to the hopper 20. The hopper is a rectangular-shaped box, minus a bottom, having an adjustably-mounted board that forms the head therefor. The hopper 20 is so positioned in the guideways 17 that the lower end thereof will slide over and in contact with the top of the mold 3 and remove the surplus material from the mold, when said hopper is moved horizontally from over the former. The bottom of the hopper 20 is practically open except at intervals where narrow cleats 26 pass transversely thereof. These cleats are intended to close the spaces 25, that exist between the individual molds, which spaces are necessary to permit the molds to be expanded to free the molded articles, and thus prevent the dissemination of the material through said spaces when the hopper is moved over the mold.

As previously stated, the head 30 of the hopper is adjustably mounted, so that it may be moved into any inclined position, and forms a seat for mounting the cutting-plates 31. These plates remove the surplus material from the molds 3 and are adjustably secured by means of the screws 32, so that they may be adjusted to compensate for the wear. The adjustability of the head 30 permits the cutting-plates 31 to be set any angle, so that the cutting power of the plates 105 can be materially increased when desired. Experience has proven that the more dense the material the more inclination from the

perpendicular should be imparted the cutting-plates 31 to lessen the cutting resistance.

The adjustable member or head 30 of the hopper 20 is provided with the spring-metal trowels 34, which are drawn over the exposed faces of the molded articles from which the cutting-plates removed the surplus material, leaving a smooth and finished surface. The resiliency of the trowels keeps them in contact with the molded articles while the hopper 20 is moved, and their flexibility permits them to be bent to conform to the angle into which the head 30 may be placed.

It will be noted that the hopper-frame is provided with a floor 40, on which the open bottom of the hopper slides, so that when the hopper is drawn over said floor the latter will catch and retain the surplus material carried by said hopper. On the succeeding movement of the hopper the surplus material is removed from the floor 40 and is dumped into the succeeding empty mold.

When the hopper 20 is moved into the position shown in Fig. 2 of the drawings, the straps 10 are removed from the hooks 9, that form the locks for securing the two parts of the upper frame together, when the member 5 of the upper frame is allowed to swing backward into vertical position and carrying the hopper-frame and hopper with it. The front member 6 of the upper frame may also be swung backward, (see Fig. 4,) leaving the way for the removal of the mold 3 free from obstruction. The pallet-board, with the molded articles, may then be removed and another board and mold substituted, when the operation as heretofore set forth is repeated.

Having thus fully described my said invention, what I desire to secure by Letters Patent, is—

1. In a device of the character described, the combination of the mold, a feed device movably mounted over the mouth of the mold and adapted to direct the material to said mouth, a cutting device carried by the feed device for removing the surplus material from the top of the mold, a receptacle for catching said surplus material and means permitting lateral movement of said feed and cutting devices.

2. In a device of the character described, the combination of the mold, a feed device movably mounted over the mouth of the mold, cutter-knives, a head-plate in the feed device for mounting the cutter-knives, and an adjusting means on the feed device for varying the line of inclination of both the head-plate and cutter-knives.

3. In a device of the character described, the combination of the mold, a feed device movably mounted over the mouth of the mold, cutter-knives, a head-plate in the feed device for mounting the cutter-knives, means for adjustably mounting the cutter-knives,

and an adjusting means on the feed device for varying the line of inclination of both the head-plate and cutter-knives.

4. In a device of the character described, the combination of the mold, a hopper-supporting frame pivotally mounted above the mold, a hopper supported in the hopper-frame, and means permitting reciprocatory movement of said hopper across the mouth of the mold.

5. In a device of the character described, the combination of the mold, a hopper-supporting frame pivotally mounted above the mold, a hopper supported in the hopper-supporting frame, means permitting the hopper-frame and hopper to swing away and free the top of the mold.

6. In a device of the character described, the combination of the mold, a hopper-supporting frame pivotally mounted above the mold, a hopper movably mounted in the hopper-supporting frame, a floor in the hopper-supporting frame to form the bottom for the hopper when the latter stands in shifted position, and means permitting lateral movement of said hopper.

7. In a device of the character described, the combination of the mold, a feed device movably mounted over the mouth of the mold, means permitting movement of said feed device across the mouth of the mold, and trowels carried by the hopper to engage and smooth the exposed surface of the molded article.

8. In a device of the character described, a mold unit composed of a plurality of individual molds, a feed device susceptible to move across the mouths of said individual molds, and means carried by said feed device to smooth the freshly-cut surfaces of the molded articles.

9. In a device of the character described, a mold unit composed of a plurality of individual molds, a feed device mounted so as to be operatively movable in a right-angle plane line of the mouths of the individual molds, cutter-knives carried by the feed device, and means on the feed device for varying the line of inclination of said cutter-knives.

10. In a device of the character described, a mold unit composed of a plurality of individual molds, a feed device mounted so as to be operatively movable in a right-angle plane line of the mouths of the individual molds and adapted to simultaneously fill said molds, means carried by the feed device for removing the surplus material from the tops of the molds, and a receptacle for catching said surplus material.

11. In a device of the character described, a mold unit composed of a plurality of individual molds, a feed device mounted so as to be operatively movable in a right-angle plane line of the mouths of the individual molds, and adapted to simultaneously fill said molds,

means carried by the feed device for removing
the surplus material from the tops of the
molds, a receptacle for catching said surplus
material, and means carried by the feed de-
vice to smooth the freshly-cut surfaces of the
5 molded articles.

In witness whereof I have hereunto set my

hand and seal at Indianapolis, Indiana, this
8th day of August, A. D. 1905.
